UNITED STATES PATENT OFFICE.

ALBERT ANDRES, OF NIEDER WALLUF, GERMANY.

HEEL-MAKING MACHINE.

SPECIFICATION forming part of Letters Patent No. 440,342, dated November 11, 1890.

Application filed August 24, 1889. Serial No. 321,822. (No model.)

To all whom it may concern:

Be it known that I, ALBERT ANDRES, foreman, a subject of the King of Prussia and Emperor of Germany, and a resident of Nieder 5 Walluf, in the Kingdom of Prussia, German Empire, have invented certain new and useful Improvements in Machines for Manufacturing and Affixing the Heels to Boots or Shoes, of which the following is an exact description.

10 My invention relates to a machine by means of which the various layers of leather forming the heel of the boot or shoe, after having been first stamped out and at the same time bored by the method usually in practice, are 15 nailed together and to the shoe, then the covering or bottom layer of the heel separately nailed on, and the straight side of the heel then cut even.

15 In order to make my invention more clear, I refer to the accompanying drawings, which form part of this specification, and in which similar letters and figures denote similar parts throughout the several views.

Figure 1 is a sectional elevation of the machine along the line $\alpha\beta$ in Fig. 2. Fig. 2 is a 20 plan of the machine with the upper part cut away along line $\epsilon\delta$ in Fig. 4. Fig. 3 is a 25 sectional plan of the machine along line $\gamma\delta$ in Fig. 4. Fig. 4 is a side elevation of the 30 machine. Fig. 4^a shows the shape of the groove in hammer L. Fig. 5 is a plan of the 35 holding-block R' R² and table A. Fig. 6 is a section on line $\alpha'\beta'$ in Fig. 5. Fig. 7 is a plan of the nailing-block l. Fig. 8 shows a section 40 through a layer of leather cut out and punched. Fig. 9 shows a plan of Fig. 8. Fig. 45 shows a section of the covering or bottom layer for the heel. Fig. 11 is a plan of the same. Fig. 12 shows a vertical section through the block for fixing the last layer to the heel. Fig. 13 shows a plan of this block. Fig. 14 shows a section through the knife-block for 50 shaving off the heel smooth. Fig. 15 shows a plan of the same.

The heels are made in the usual manner by 45 layers of leather stamped out and fixed together by means of brads. In my arrangement the layers are punched at the same time as they are stamped with the holes for 50 the brads, and are punched in such a manner that the brads are bent in being driven into the form of the heel, as will be seen from

Fig. 6. This is effected by the formation of the various dies, which, however, form no part of my present invention. The layers of 55 leather forming the heel are now, held together by means of a piece of string or a couple of brads driven through them. The heel is now ready for the machine.

The machine is constructed in the following manner: A is a circular table, which revolves round its center bolt B. In the table A are three circular openings 1 2 3, in which three dies are placed. These dies are shown in section in Figs. 6, 12, and 14, and serve, first, 60 to drive the brads through the heel, holding the layers forming the same together and at the same time onto the upper part of the shoe, Fig. 6; second, to fix the covering or bottom layer onto the heel, Fig. 12; third, to cut the 65 straight side of the heel smooth, Fig. 14. The circular table A revolves on the frame G of the machine.

In the front part of the machine is a vertical cylindrical guide, in which the piston or 70 hammer L moves. This hammer L is driven by the crank J on the end of shaft H, and shaft H is driven in its turn by means of gearing-wheels G and E and sheave-pulleys D D from a main driving-shaft. The roller 75 K of crank J works in a peculiarly-shaped groove in the lower part of the hammer L. (Shown in Fig. 4^a.) On the upper part of hammer L is a dovetail projection, which, as to be seen in plan in Figs. 7, 13, and 15, is 80 curved to a radius drawn from the center of the disk A. In its lowest position the top of hammer L is flush with the surface of the 85 machine-table C.

Into one of the openings 1, 2, or 3 in disk 90 A is placed the apparatus for nailing the heel-pieces together and onto the boot, Fig. 6. This apparatus consists of a plate i, having on its under side a groove, which when the disk A revolves dovetails over the projection 95 on the hammer L. On its upper side it contains the studs k k, which drive the brads into the heels. The plate i has, further, two bolts guided in the holes in the guide-block m, by means of which the studs k k and block 100 l, containing the brads which slide in guide-block m, are drawn downward after the brads have been driven into the heel. The brads are placed into the block l by a special appa-

ratus forming no part of this invention. The apparatus for fastening on the bottom layer to the heel placed into the second opening in disk A is in its main points the same as that 5 just described, as will be seen from Fig. 12, with the addition that besides the brads it contains the layer of leather. The third apparatus consists of a knife k^2 for cutting or shaving off the front of the heel, and is so 10 simple and clearly shown in Figs. 14 and 15 that further explanation is unnecessary. During this third operation the two blocks $R' R^2$, between which the heel-piece has up to the 15 present been clamped by means of the two eccentrics T T and handle S, must be loosened, when projection n^2 on disk A comes under the nose o and pushes the two blocks apart, in order to make place for the knife k^2 . This is done by hand, the handle S simply 20 being thrown upward, Fig. 14, when the shavings will fall through the slanting opening k^3 .

Turning on its center Q' is a disk Q, on the upper surface of which is a cam Q^2 . (Shown in dotted lines in Fig. 2.) This disk Q is 25 driven by means of bevel-wheels $J' J'$ from shaft H. The one end of bent lever P works in the cam Q^2 of disk Q. The bent lever P itself is pivoted at P' , and its long arm is connected by means of connecting-rod o' 30 with the middle of lever-arm m^0 , which is pivoted to the center bolt B. On the other end of lever-arm m is a ratchet n , which works in teeth on the under rim of the disk A, through a slit n' in the table C of the machine. The cam Q^2 is so formed that the disk 35 A shall make one revolution to each of three revolutions of the disk Q, and, further, that as each opening 1, 2, or 3 in disk A comes over the piston or hammer L the disk shall 40 stand still long enough to allow the hammer to pass into the opening and drive the brads into the heel and pass down again. As will be clearly seen from the drawings, the disk A will remain still so long as the roller on the 45 end of bent lever P remains in the concentric part of the cam Q^2 .

The boot or shoe is held in position during the process of affixing the heel to the same by means of the dolly v, fixed at its upper 50 end to the frame W. The frame W is vertically movable by means of its rods $x x$, running in the guides $U' U^2$, and is pressed down tightly onto the shoe during the operation by the following mechanism:

55 On the shaft H is a pinion h , Fig. 3, which gears into a driving-wheel g on the shaft f , running in bearings in the machine-frame, and this shaft f carries a cam e , which works the arm p of the bent lever $p z'$ by means of 60 the roller on the end of the same. Bent lever $p z'$ is pivoted to the frame of the machine at p' , and its other arm z' is pivoted to lever-arm z^2 , and at the same time to the connecting-rod y . Lever-arm z^2 is pivoted at its 65 lower end to the guide-rod x of the frame W. The double lever $z' z^2$ is connected with the two lever-arms $z z$ by means of the rod y , and

these two lever-arms are pivoted together to rod y at y' . The upper end of the upper arm z is pivoted to the machine-frame, and the 70 lower end of the lower arm z to the guide-rod x of frame W. The shaft f is so geared to shaft H that during the time while the disk a is making one revolution—that is to say, while the three operations necessary for fixing the heel-layers together and to the shoe, then fixing the bottom layer to the heel, and, thirdly, shaving the inside of the heel smooth, are taking place—the concentric part of the cam e presses the arm p of bent lever $p z'$ upward, Fig. 4, and 75 the levers $z z z' z^2$, having their upper ends $p' p^2$ fixed, press with their lower ends the guide-rod x downward, thus holding the shoe firmly in its place. When the operations are finished, the roller on end of arm p comes into 80 the notch in the cam e and the guide-rod of frame W are released, when the frame W may be turned outward by means of handle W' , as shown in dotted lines in Fig. 1, and the 85 shoe removed.

90 The working of the machine is the following: The layers of leather forming the heel are bound together and placed between the two blocks $R' R^2$. The upper part of the shoe is then placed on the dolly v and held in its proper position over the heel. The machine is now set in motion. The cam e at first comes under the bent lever $p z'$ and presses it upward, whereby by means of levers $z z z' z^2$, and y the dolly v is jammed tightly down 95 onto the shoe. The disk A has now revolved so far that the apparatus 1 is brought over and dovetailed into the hammer L. This rises by means of crank J and drives the brads into the heel, nailing the layers of the 100 same together and nailing the heel onto the shoe. The hammer then sinks again. The disk A now revolves farther and opening 2 is brought over hammer L. Hammer L rises again and the bottom layer is fastened to the 105 heel in the manner described. It then sinks again and apparatus 3 comes over the hammer. At this moment the blocks $R' R^2$ are released by throwing up handle S, as described, and by projection n^2 coming under nose o to allow 110 the knife k^2 , which faces up one side of the heel. By this time the notch in cam e has come under arm p of bent lever $p z'$ and the same sinks, releasing the dolly v , and the shoe, with blocks $R' R^2$, may be removed from the 115 machine. The blocks are then removed from the heel.

Having thus fully described and ascertained the nature of my said invention, what I claim, and desire to secure be Letters Patent of the 120 United States, is—

1. In a heel-attaching machine, in combination with the nailing and breasting devices thereof, the table A, having three cylindrical openings 1, 2, and 3, and having a projection n^2 on its rim and teeth on its under edge, pivot 125 B, around which the table is adapted to revolve, and mechanism to revolve the same, consisting of ratchet n and arm m^0 and con- 130

nections between said arm and the driving-shaft, as described.

2. In a heel-attaching machine, in combination with the nailing and breasting devices thereof, the table A and mechanism to revolve the same, consisting of arm m^0 , ratchet n , attached to end of arm m^0 , pivot B, around which the arm m^0 is adapted to revolve, bent lever P, pivot P', around which lever P is adapted to oscillate, connecting-piece Q', attached to end of lever P and adapted to transmit the revolving motion from lever P to arm m^0 , disk Q, having an eccentric-groove Q^2 adapted to move lever P, pivot Q', around which disk Q is adapted to revolve, and connections between said disk and the main driving-shaft, in the manner described.

3. In a heel-attaching machine, in combination with the nailing and breasting devices thereof, the table A and hammer L, having dovetail projection on its upper end, said projection being radial with the center point of table A and adapted to slide into radial dovetail grooves of the nailing and breasting devices contained in table A at each revolution of the same, in the manner as described.

4. In a heel-attaching machine, in combination with the nailing and breasting devices thereof, table A, hammer L, and mechanism for operating the same, consisting of frame W, bearing the handle W', and the dolly v, attached to the midst of the frame W and adapted to hold the shoe in place, the guides U' U², and the guide-rods x x, movably fixed in the

guides U' U² and adapted to allow a vertical motion of frame W and dolly v, inward projections of the lower ends of the guides U' U², adapted to guide the pieces R' and R² forming the shoe-block, the eccentrics T T and handle S, mounted on block R' and adapted horizontally to move the said shoe-block, the projection n² on table A, and nose o on piece R, adapted to open the block-shoe for the breasting of the heel, in the manner as described.

5. In a heel-attaching machine, in combination with the nailing and breasting devices thereof, table A, hammer L, dolly v, and mechanism to move the latter, consisting of frame W, bearing the handle W', and the dolly v, attached to the midst of the frame and adapted to hold the shoe in place, the guides U' U², the guide-rods x x, movably fixed in the guides U' U² and adapted to allow a vertical motion of the dolly v, the levers z', z z, z², and y, adapted to raise the guide-rods x x, the cam e, mounted on shaft f, the lever p, moved by the said cam e and adapted to transmit this motion to the intermediate lever-connections z' z z z² y, and the gear-wheels h and g, geared to driving-shaft H and adapted to revolve cam e, in the manner as described.

In witness whereof I have hereunto set my hand in presence of two witnesses.

ALBERT ANDRES.
